[57] CLAIM

The ornamental design for a cleated shoe sole, substantially as shown and described.

DESCRIPTION

FIG. 1 is a bottom-right perspective view of a cleated shoe sole showing my new design;
FIG. 2 is a bottom plan view thereof;
FIG. 3 is a left side elevational view thereof;
FIG. 4 is a rear elevational view thereof;
FIG. 5 is a front elevational view thereof;
FIG. 6 is a cross-sectional view as taken from line 6—6 of FIG. 2.
